UNITED STATES PATENT OFFICE.

FREDERICK D. WILSON, OF MOLINE, ILLINOIS, ASSIGNOR TO DEERE AND COMPANY, OF MOLINE, ILLINOIS, A CORPORATION OF ILLINOIS.

MOWING-MACHINE.

1,313,443.

Specification of Letters Patent.

Patented Aug. 19, 1919.

Application filed January 19, 1917. Serial No. 143,371.

To all whom it may concern:

Be it known that I, FREDERICK D. WILSON, a citizen of the United States, and a resident of Moline, in the county of Rock Island and State of Illinois, have invented certain new and useful Improvements in Mowing-Machines, of which the following is a specification, reference being had to the accompanying drawings.

10 My invention relates to mowing machines and particularly to that type of machine which has its cutter-bar arranged to be lifted by means of a lever from a horizontal operative position to a substantially vertical 15 inoperative position, and it has for its principal object the provision of simple and improved means for lifting the cutter-bar and for locking it in either of a plurality of raised positions and for unlocking it therefrom. It is one of the objects of my invention to provide lifting mechanism for a cutter-bar so arranged and constructed that by the manipulation of a foot-lever the cutter-bar may be unlocked and lowered into 20 working position. It is another object of my invention to provide means, comprising a foot-lever, for lifting and locking the cutter-bar in either of a plurality of positions so arranged and constructed that when the 25 cutter-bar is moved into either of said positions the foot-lever will be held in elevated position ready for an operative stroke. It is another object of my invention to provide means for lifting the cutter-bar by the use 30 of two levers, by one of which levers the bar can be held temporarily in raised position, the arrangement and construction being such that when the other lever is released the cutter-bar will be automatically locked 35 in raised position. It is another object of my invention to provide a construction of the type just described so arranged and constructed that upon a subsequent stroke of the last-mentioned lever the cutter-bar will 40 be released for its downward movement. It is still another object of my invention to improve mowing machines in sundry details hereinafter pointed out. The preferred means by which I have accomplished my 45 several objects is illustrated in the drawings and is hereinafter specifically described. That which I believe to be new and desire 50 to cover by this application is set forth in the claims.

In the drawings:

55 Figure 1 is a plan view, partly broken away, illustrating a mowing machine embodying my improved construction;

Fig. 2 is a vertical section taken substantially on line 2—2 of Fig. 1, but with the 60 driver's seat and its supporting bar omitted.

Fig. 3 is a view similar to Fig. 2, but showing the position of the parts when the cutter-bar is raised, but not locked against downward movement;

Fig. 4 is a view similar to Fig. 3, but showing the position of the parts when the cutter-bar is locked in raised position;

Fig. 5 is an enlarged detail illustrating a portion of the lifting mechanism in the position it occupies when the cutter-bar is in locked position as shown in Fig. 4;

Fig. 6 is an enlarged detail of the parts shown in Fig. 5 in the position they occupy when the cutter-bar is in the position shown 75 in Fig. 2;

Fig. 7 is an enlarged detail of the same parts, but showing the position they occupy when the cutter-bar is in the position shown in Fig. 3;

Fig. 8 is an enlarged detail illustrating a 80 part of the locking means; and

Fig. 9 is an enlarged detail illustrating the construction of the foot-lever.

Referring to the several figures of the 85 drawings, in which corresponding parts are indicated by the same reference characters,—

15 indicates the framework of the machine supported by means of an axle 16 having carrying wheels 17—18 mounted thereon and connected therewith through the medium of the usual ratchet mechanism 17^a—18^a. Mounted upon the axle 16 is a gear system for taking power from the axle 90 to drive the sickle operating means, indicated in general by the numeral 19. Such gear system may be of any approved type, and as indicated by dotted lines in Fig. 1 it comprises a large bevel gear 20 that is 100 in mesh with a bevel pinion 21 fixedly mounted on a forwardly-extending shaft 22 that thus receives power from the gear system 19, the shaft 22 having fixedly mounted on its forward end a driving head in the 105 form of a crank wheel 23 which is connected by means of a pitman 24 with a sickle 25 slidably mounted in a cutter-bar 26 which

is mounted in position as hereinafter described. The frame 15 is provided, in the construction shown, with a tongue 27 of any suitable type by means of which the machine is to be drawn across the field, and is further provided with a seat 28 of any suitable type.

The means for mounting the cutter-bar upon the frame 15 comprises a yoke 29 (see Fig. 2), such yoke being pivotally mounted upon the forward turned end of a push-bar 30 and the adjacent end of a drag-bar 31 which in turn is pivotally connected at its opposite end with the frame 15 in front of the crank wheel 23. The yoke 29 is further connected with the frame 15 by means of a link 32 pivotally connected at its forward end with an arm 33 that is preferably formed integrally with said yoke, the link 32 being connected at its rear end with a lever 34 of any suitable type pivotally mounted upon the frame 15 and adjustable relative thereto along a segmental rack 35 carried by the frame. As will be readily understood, by an adjustment of the lever 34 the yoke 29 can be tilted on a transversely-extending axis relative to the framework. The cutter-bar 26 is pivotally connected to the yoke 29 upon an axis extending longitudinally of the machine by means of a suitable shoe 36 to which the inner end of said cutter-bar is fixedly connected.

By reason of the bars 30 and 31 being pivotally connected with the frame 15, the yoke 29 and the cutter-bar 26 are movable up and down relative to the frame 15, while at the same time the cutter-bar 26 is movable relative to the yoke 29 upon the longitudinally-extending axis of the shoe 36 upon said yoke. The parts so far described are of the ordinary type well understood in the art and form in and of themselves no part of my present invention.

The means for raising the yoke 29 and the cutter-bar 26 relative to the frame 15 comprises a bell-crank lever or sector 37 which is pivotally mounted upon the framework 15. The forward end of the forwardly-extending arm of the sector 37 is provided with a flexible connector 38 which extends about a spirally-grooved sheave 39, and from thence to the shoe 36 to which it is connected at a point beyond the axis of the shoe, such flexible connector in its passage to the point where it is attached to the shoe passing over a suitable arm or standard 40 fixedly mounted upon the shoe, and which may be grooved as shown to properly receive and guide the said flexible connector, or which may, if deemed advisable, be provided with a suitable grooved pulley for the connector to run over. By reason of passing over this upright arm or standard a pull is had on the shoe of a character that will cause the cutter-bar to turn on its pivotal connec-

tion with the yoke, after the upward movement of the push-bar 30 has been checked as hereinafter described, and thereby be elevated as indicated in Fig. 3 and as more particularly described hereinafter. The sheave 39 is journaled upon a bracket 41 which is mounted upon the drag-bar 31 adjacent to the yoke 29. The arrangement and construction of the parts are such that, upon a turning of the sector 37 in counterclockwise direction in Fig. 2 from the position shown therein, the sheave 39 and the yoke 29 are moved upward relative to the framework, carrying upward with them the shoe 36 and the cutter-bar 26. When in the upward movement of the parts as just described the push-bar 30 comes in contact with a suitable stop formed on the underside of the framework so as to be incapable of further upward movement, a continued rotation of the sector 37 in counterclockwise direction in Fig. 2 serves through the medium of the flexible connector 38 to turn the shoe 36 relative to the yoke 29 upon its horizontal axis, whereby the cutter-bar 26 and the sickle 25 slidably carried thereby are swung upward substantially in a vertical position as shown in Fig. 3, the sheave 39 being adapted to rotate to permit of such turning movement. The stop referred to with which the push-bar 30 comes in contact is, in the construction shown, the bearing plate 52 that is hereinafter referred to.

Means is provided in connection with the sector 37, adapted upon the rocking of the sector in counterclockwise direction in Figs. 2, 3 and 4, to throw out of operation the sickle-driving mechanism. This means comprises a link 42 the turned forward end of which is slidably mounted in a slot 43 in the sector 37. The link 42 is pivotally connected at its rear end with an arm 44 depending from a foot-lever 45 pivotally mounted upon the framework 15, the construction being such that when the sector 37 is turned in counterclockwise direction in Fig. 2, the foot-lever 45 will be rocked about its axis also in counterclockwise direction in said figure. By reason of the slotted connection of the link 42 with the sector 37, the foot-lever 45 is adapted to be operated independently of the rocking of the sector 37 when such sector stands in the position shown in Fig. 2. The foot-lever 45 is provided at its forward end with a cam 46 which co-operates with a suitable head 47 upon a transversely-extending rod 48, in the construction shown the rod 48 passing through a suitable slot in the cam 46. The rod 48 is arranged to co-operate with the gear system 19 in such manner that upon the turning of the foot-lever 45 in counterclockwise direction in Fig. 2, the rod 48 will be moved longitudinally to open the gear system, serving thus to stop the reciprocation of the 130

sickle 25 relative to the cutter-bar 26. When the foot-lever 45 is turned in clockwise direction in said Fig. 2 by the rocking of the sector 37, the rod 48 will, of course, 5 be moved longitudinally to close the gear system, thus starting the reciprocation of the sickle 25. This last-named longitudinal movement may be effected by means of a coiled spring (not shown) or by any other 10 suitable means. In the preferred construction the arrangement is such that the rod 48 opens and closes the gear system automatically at about the time the cutter-bar starts to turn on its horizontal axis relative to the 15 yoke 29. It is thus seen that the cutter-bar can be raised a short distance, such as is necessary for a proper turning at corners, without throwing the cutting apparatus out of operation.

20 A spring 49 connected to the sector 37 and to the framework 15 in rear of such sector serves to assist in turning the sector in counterclockwise direction in Figs. 2 and 3, serving also to counterbalance a portion of 25 the weight of the cutting apparatus in order to decrease the friction of the cutter-bar upon the ground and in order to transfer the principal weight of the cutting apparatus to the frame where it adds traction 30 to the wheels.

The means for supporting the sector 37 in position upon the framework and for rocking such sector for operating the cutter-bar comprises a foot-lever 50, shown in detail in Fig. 9. This foot-lever comprises a transversely-extending portion 51 which is journaled upon the framework 15 by means of a bearing-plate 52 as is probably best shown in Fig. 8. As is best shown in Fig. 40 9, the end portion 53 of the laterally-extending arm 51 of the lever 50 is offset relative to the axis upon which the lever is connected with the frame 15, the part 53 serving to provide a journal for the sector 37 in 45 an offset or cranked position relative to the pivotal mounting of the lever 50. The sector 37 is provided with a handle or lever 54 fixedly mounted thereon within convenient reach of an operator upon the seat 28. As 50 will be readily understood, when the operator swings the lever 54 backward from the position shown in Fig. 2 into the position shown in Fig. 3, the sector 37 will be given an operative stroke for first raising the yoke 55 29 and the cutting apparatus and then swinging the cutter-bar upward relative to the yoke 29, as above described.

Inasmuch as the sector 37, by which the weight of the cutting apparatus is supported during the lifting operation, is mounted upon an offset portion of the lever 50, such offset portion 53 of the lever 50 will have a tendency always to move toward its lowermost position relative to the portion 51 of the lever, except as pressure is applied to

the lever 50 by the foot of the operator or as the sector 37 is supported against downward movement by some other suitable stopping or supporting means. Such supporting means is provided, comprising a combination stop and latch member 55 rigidly mounted upon the framework 15. The sector 37 is provided with a suitable flange 56 which rests upon the upper end of the member 55 when the cutting apparatus is in 70 operative position, as is shown in Fig. 6, serving to hold the offset portion 53 of the foot lever in raised position relative to the portion 51 as is clearly indicated in said Fig. 6. When the lever 54 and the sector 80 37 are rocked in counterclockwise direction in Fig. 6, the flange 56 travels along the upper end of the stop 55 until a step 57 in such flange arrives opposite the rear face of the stop 55, whereupon the sector 37 is 85 adapted to move downward relative to the stop 55 by reason of the weight of the cutting apparatus mounted upon the offset portion 53, such movement taking place unless pressure is applied to the foot-lever 50 so 90 as to hold the lever against turning. When the step 57 has engaged the rear edge of the stop 55, the lever 54 can then be released and the sector will be held against movement in clockwise direction, the cutting apparatus being thus held in its elevated position.

If the lever 54 be then given a further backward movement, the intermediate portion of the flange 56 travels backward along the stop member 55 serving to hold the portion 100 53 of the foot-lever in its raised position. When the sector 37 has been turned sufficiently to bring a step 58 in the flange 56 opposite the rear edge of the stop or latch member 55, the sector 37 is again permitted 105 to move downward, carrying the step 58 into latching engagement with the member 55, except as such movement is prevented by downward pressure upon the foot-lever 50.

The step 57 is so positioned on the flange 110 56 as to come into operative position relative to the latch member 55 at about the time when the yoke 29 reaches its uppermost position and before the cutter-bar 26 begins to turn upon its axis relative to the yoke 29. 115 The step 58 is so positioned as to come into operative engagement with the latch member 55 at about the time when the cutter-bar 26 reaches its substantially vertical inoperative position. As will be seen by an inspection of Figs. 5, 6 and 7, the flange 56 is not concentric about the portion 53 of the foot-lever 50, but has a slight cam action serving to raise the portion 53 gradually relative to the portion 51 of the foot-lever as 120 the sector 37 is moved in counterclockwise direction in said figures through the medium of the handle or lever 54. It will be understood that as the lever 54 moves backward, the rear end of the foot-lever 50 will 125 130

move gradually downward as the portion 53 is moved upward, except that when the steps 57 and 58 are brought into engagement with the stop or latch member 55 the rear end of the foot-lever 50 will be given abrupt movements upward corresponding to the abrupt downward movements of the portion 53. Whenever the sector 37 is held in turned position by reason of the engagement of one of the steps 57-58 with the latch member 55 serving to hold the cutter-bar in elevated position, and when it is desired to lower the cutter-bar, this can be accomplished by a downward pressure upon the rear end of the foot-lever, such downward pressure serving to raise the stepped flange 56 relative to the member 55 whereby the sector is free to swing in clockwise direction in Figs. 5, 6 and 7 for permitting the downward movement of the cutting mechanism.

The foot-lever 50 is also adapted to assist in the initial movement of the sector 37 in counterclockwise direction in Figs. 2, 3 and 4, or to give such movement to the sector independently of the lever 54, this result being effected through the medium of an arm 59 fixedly mounted upon the end of the offset portion 53 of the foot-lever, such arm normally underlying a set-screw 60 adjustably mounted in the sector 37. With the parts in the position shown in Fig. 6, in which position such parts stand when the cutter-bar is in its operative cutting position, upon a downward stroke of the rear end of the lever 50 the arm 59 is moved upward serving to swing the sector 37 rearwardly about the axis of the portion 51 of the foot-lever. As will be readily understood, this serves to raise the flange 56 out of contact with the member 55, wherefore the sector 37 is not normally locked in position upon such a movement of the foot-lever 50. When the sector has been swung backward in this manner by the use of the foot-lever 50, if the operator desires to lock the cutting apparatus in its raised position he can accomplish this result by holding the lever 54 against forward movement and by removing the pressure upon the foot-lever. The sector 37 is thus held against rocking, but is permitted to move downward into contact with the stop member 55 as the weight of the mechanism turns the lever 50 about the journal portion 51 so as to bring the portion 53 to its lowermost point as above described. The foot-lever is capable of turning the sector 37 through only a portion of its stroke, being capable of swinging the step 57 well past the rear edge of the stop member 55. If the sector 37 be given a backward movement through the medium of the foot-lever 50, the step 57 can be brought into engagement with the stop member 55 by a quick upward movement of such lever 50 without the necessity for grasp-

ing the lever 54, but ordinarily the lever 54 would be used in this operation. If it is desired to raise the cutter-bar to its vertical position from its lowered operative position, this can be accomplished either by a movement of the lever 54 by itself, or by a stroke of the lever 54 assisted by a downward movement of the lever 50.

By the provision of the raising and locking mechanism as above described, any method of manipulation of the levers 50 and 54 for raising and locking the cutting mechanism serves to move the lever 50 into raised position whenever the locking is effected, and the mechanism is adapted in any event to be unlocked for lowering the cutting mechanism by a subsequent downward movement of the foot-lever 50.

What I claim as my invention and desire to secure by Letters Patent, is—

1. In a mowing machine, the combination of a frame, a cutter-bar movable relative to said frame, a foot-lever operatively connected with said cutter-bar for raising said bar by a downward stroke of the lever, means for locking said cutter-bar in raised position, and means actuated by the locking of said cutter-bar in raised position serving to raise said foot-lever into position for another downward stroke.

2. In a mowing machine, the combination of a frame, a cutter-bar movable relative to said frame, a foot-lever operatively connected with said cutter-bar for raising said bar by a downward stroke of the lever, and means for locking said cutter-bar in raised position, said lever by a subsequent downward stroke from its original position releasing said cutter-bar from raised position.

3. In a mowing machine, the combination of a frame, a cutter-bar movable relative to said frame, a foot-lever operatively connected with said cutter bar for raising said bar by a downward stroke of the lever, and means operable upon the release of the lever with the cutter-bar in raised position for locking said cutter-bar in raised position, said lever by a subsequent downward stroke releasing said locking means for permitting downward movement of the cutter-bar.

4. In a mowing machine, the combination of a frame, a cutter-bar movable relative to said frame, a foot-lever operatively connected with said cutter-bar for raising such bar by a downward stroke of the lever, and means for locking the cutter-bar in raised position and simultaneously causing said lever to turn to the position that it occupied before said cutter-bar was raised.

5. In a mowing machine, the combination of a frame, a cutter-bar movable relative to said frame, means comprising a foot-lever operatively connected with said cutter-bar for raising said cutter-bar in substantially horizontal position by a downward stroke of

- the lever and comprising also a device independent of said foot-lever for raising said cutter-bar into substantially vertical position, means for locking said cutter-bar in 5 raised position, and means actuated by the locking of the cutter-bar in raised position serving to raise said foot-lever into position for another downward stroke. 70
6. In a mowing machine, the combination 10 of a frame, a cutter-bar movable relative to said frame, means comprising a foot-lever operatively connected with said cutter-bar for raising said cutter-bar in substantially horizontal position by a downward stroke of 15 the lever and comprising also a device independent of said foot-lever for raising said cutter-bar into substantially vertical position, means for locking said cutter-bar in either its raised horizontal position or its 20 raised vertical position, and means actuated by the locking of the cutter-bar in either position serving to raise said foot-lever into position for another downward stroke. 85
7. In a mowing machine, the combination 25 of a frame, a cutter-bar movable relative to said frame, a lever operatively connected with said cutter-bar for raising said bar by a stroke of the lever, a second lever operatively connected with said cutter-bar 30 for also raising said cutter-bar, and means actuated by an operative bar-raising stroke of said second lever for locking said bar in raised position, the arrangement being such that upon the locking of said bar in raised 35 position said first-named lever is returned to position for another stroke. 90
8. In a mowing machine, the combination 40 of a frame, a cutter-bar movable relative to said frame, a lever operatively connected with said cutter-bar for raising said bar by a stroke of the lever, a second lever operatively connected with said cutter-bar for also raising said bar, and means for locking said cutter-bar in raised position 45 when the first-named lever is released and the cutter-bar is held in raised position through the medium of said second lever. 100
9. In a mowing machine, the combination 50 of a frame, a cutter-bar movable relative to said frame, a lever operatively connected with said cutter-bar for raising said bar by a stroke of the lever, a second lever operatively connected with said cutter-bar for also raising said bar, means for locking 55 said bar against movement when the first-named lever is released and the cutter-bar is held in raised position through the medium of said second lever, and means actuated by the locking of said cutter-bar in 60 raised position serving to return said first-named lever to position for another operative stroke. 115
10. In a mowing machine, the combination 65 of a frame, a cutter-bar movable relative to said frame, a lever operatively connected with said cutter-bar for raising said 120
- 70
- 75
- 80
- 85
- 90
- 95
- 100
- 105
- 110
- 115
- 120
- 125
- 130
- nected with said cutter-bar for raising said bar, a second lever operatively connected with said cutter-bar for also raising said bar, means for locking said bar against movement when the first-named lever is released and the cutter-bar is held in raised position through the medium of said second lever, and means actuated by the locking of said cutter-bar in raised position serving to return said first-named lever to position for another operative stroke, said first-named lever when given such second-named stroke releasing said cutter-bar from raised position.
11. In a mowing machine, the combination of a frame, a cutter-bar movable relative to said frame, a lever operatively connected with said cutter-bar for raising said bar, a second lever operatively connected with said cutter-bar for also raising said cutter-bar, and means actuated by an operative bar-raising stroke of said second lever for locking said bar in raised position and simultaneously causing said first-named lever to turn into such position that upon a subsequent operative stroke thereof it will release said bar from raised position. 90
12. In a mowing machine, the combination of a frame, a cutter-bar movable relative to said frame, a lever operatively connected with said cutter-bar for raising said bar in substantially horizontal position, a second lever operatively connected with said cutter-bar for also raising by a partial operative stroke said cutter-bar in substantially horizontal position and by a further operative stroke raising said cutter-bar to substantially vertical position, and means actuated by an operative bar-raising stroke of said second lever for locking said bar in either its horizontal raised position or its vertical raised position, said first-named lever by a subsequent operative stroke releasing said bar from raised position. 100
13. In a mowing machine, the combination of a frame, a cutter-bar movable relative to said frame, a lever operatively connected with said cutter-bar for raising said cutter-bar in substantially horizontal position, a second lever operatively connected with said cutter-bar for raising by a partial operative stroke said cutter-bar in substantially horizontal position and by a further operative stroke raising said cutter-bar to substantially vertical position, and means for locking said cutter-bar in raised position when the first-named lever is released with the cutter-bar held in either its horizontal raised position or its vertical raised position through the medium of said second lever. 115
14. In a mowing machine, the combination of a frame, a cutter-bar movable relative to said frame, a lever operatively connected with said cutter-bar for raising said 120
- 125
- 130

- cutter-bar in substantially horizontal position, a second lever operatively connected with said cutter-bar for also raising by a partial operative stroke said cutter-bar in 5 substantially horizontal position and by a further operative stroke raising said cutter-bar to substantially vertical position, and means actuated by an operative bar-raising stroke of said second lever for locking said 10 bar in either its horizontal raised position or its vertical raised position, the arrangement being such that upon the locking of said bar in either of its raised positions said first-named lever is returned to its original 15 position.
15. In a mowing machine, the combination of a frame, a cutter-bar movable relative to said frame, a lever operatively connected with said cutter-bar for raising said cutter- 20 bar in substantially horizontal position, a second lever operatively connected with said cutter-bar for also raising by a partial operative stroke said cutter-bar in substantially horizontal position and by a further operative 25 stroke raising said cutter-bar to substantially vertical position, and means for locking said cutter-bar in raised position when the first-named lever is released with the cutter-bar held in either of its said two 30 positions through the medium of said second lever and simultaneously causing said first-named lever to return to its original position.
16. In a mowing machine, the combination of a frame, a cutter-bar movable relative to 35 the frame, a lifting member revolvably mounted on the frame and movable bodily slightly up and down relative to the frame while being turned, means connecting said lifting member and cutter-bar for compelling a raising of the cutter-bar when said lifting member is turned in one direction and is also bodily raised with respect to the frame, and means for locking said lifting member against turning in the reverse direction after said member has been bodily lowered with respect to the frame.
17. In a mowing machine, the combination of a frame, a cutter-bar movable relative to said frame, a lifting member revolvably mounted on said frame and movable bodily slightly up and down relative thereto, connections between said lifting member and said cutter-bar for causing the cutter-bar to be raised upon the rocking of said lifting 50 member in one direction, means serving to bodily lower said lifting member after it has been rocked and to lock it against turning in the reverse direction when said lifting member is rocked in its said bodily lowered 55 position, for further raising the cutter-bar, and a foot-lever for bodily raising said lifting member out of its said lowered and locked position.
18. In a mowing machine, the combination of a frame, a cutter-bar movable relative 60 to said frame, a lifting member revolvably mounted on said frame and movable slightly up and down relative thereto, connections between said lifting member and said cutter-bar for causing the cutter-bar to be raised upon the rocking of said lifting member in one direction, means serving to bodily lower said lifting member after it has been rocked and to lock it against turning in the reverse direction when said lifting member is rocked in its said bodily lowered position for further raising the cutter-bar, and a lever connected with said lifting member for holding the lifting member in its bodily raised position during the turning movement of the lifting member.
19. In a mowing machine, the combination of a frame, a cutter-bar movable relative to said frame, a lifting member revolvably mounted on said frame and movable bodily slightly up and down relative thereto, connections between said lifting member and said cutter-bar for causing the cutter-bar to be raised upon the rocking of said lifting member in one direction, means permitting said lifting member to be bodily lowered after it has been rocked and to lock it against turning in the reverse direction when said lifting member is rocked in its said bodily lowered position for further raising the cutter-bar, a lever connected with said lifting member for raising the lifting member bodily with respect to the frame and holding it so raised during any portion of the turning movement of said member, and a second lever connected with said lifting member for alternatively rocking the lifting member to raise the cutter-bar and lock it in raised position.
20. In a mowing machine, the combination of a frame, a cutter-bar movable relative to said frame, a lifting member revolvably mounted on said frame and movable bodily slightly up and down relative thereto, means connecting said lifting member and said cutter-bar for causing the cutter-bar to be raised upon the rocking of said lifting member in one direction, means permitting said lifting member to be bodily lowered after being rocked and to be locked against turning in the reverse direction when said lifting member is rocked in its said bodily lowered position for further raising the cutter-bar, a lever connected with said lifting member for rocking it in its bodily lowered position for raising the cutter-bar and locking it in raised position, and a second lever independent of said first-named lever for releasing said cutter-bar from raised position.
21. In a mowing machine, the combination of a frame, a cutter-bar movable relative to said frame, a lifting member revolvably mounted on said frame and movable slightly up and down relative thereto, con-

nections between said lifting member and said cutter-bar, means serving to lock said lifting member against turning in the reverse direction when said lifting member is 5 rocked in its lowered position for raising the cutter-bar, a lever adapted by an operative stroke to rock said lifting member in its lowered position for raising the cutter-bar and locking it in raised position, and a second lever for raising said member bodily to 10 free it from locked position for permitting the cutter-bar to move downward.

22. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to 15 be raised upon the rocking of said lifting member in one direction, and a stop device carried by said frame, a cam member carried by said revolvble lifting member which cam member engages said stop device to cause said lifting member to be bodily moved upward gradually as it is turned to raise the cutter-bar, said stop device and said lifting member by their engagement with each other holding said cutter-bar against moving 20 downward from raised position, and a foot lever for raising said lifting member out of engagement with said stop device.

26. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to 25 be raised upon the rocking of said lifting member in one direction, and a stop device carried by said frame, a cam member carried by said revolvble lifting member which cam member engages said stop device to cause 30 upward gradually as it is turned to raise the cutter-bar, said stop device and said lifting member by their engagement with each other holding said cutter-bar against moving downward from raised position, and a foot lever for raising said lifting member out of engagement with said stop device.

23. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to be raised upon the rocking of said lifting member in one direction, a stop device carried by said frame, and a cam member carried by said revolvble lifting member which cam member engages said stop device to cause said lifting member to be bodily moved upward gradually as it is turned to raise the cutter-bar, said stop device and said lifting member by their engagement with each other holding said cutter-bar against moving downward from raised position.

24. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to be raised upon the rocking of said lifting member in one direction, said lifting member being provided with a stepped flange extending partially about its axis of revolution, and a stop device carried by said frame with which said stepped flange engages when said lifting member is turned to raise the cutter-bar.

25. In a mowing machine, the combination of a frame, a cutter-bar movable rela-

tive to said frame, a lifting member revolvably mounted on said frame and bodily movable slightly up and down relative thereto, means connecting said lifting member and said cutter-bar for causing the cutter-bar to be raised upon the rocking of said lifting member in one direction, a stop device carried by said frame, and a cam member carried by said revolvble lifting member which cam member engages said stop device to cause said lifting member to be bodily moved upward gradually as it is turned to raise the cutter-bar, said stop device and said lifting member by their engagement with each other holding said cutter-bar against moving downward from raised position, and a foot lever for raising said lifting member out of engagement with said stop device.

26. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to be raised upon the rocking of said lifting member in one direction, a stop device carried by said frame, a cam member carried by said revolvble lifting member which cam member engages said stop device to cause 95 upward gradually as it is turned to raise the cutter-bar, said stop device and said lifting member by their engagement with each other holding said cutter-bar against moving downward from raised position, and a foot-lever that by a downward stroke turns said lifting member for raising the cutter-bar and at the same time may raise said lifting member out of engagement with said 100 stop device.

27. In a mowing machine, the combination of a frame, a cutter-bar movable relative to said frame, a lifting member revolvably mounted on said frame and bodily movable slightly up and down relative thereto, means connecting said lifting member and said cutter-bar for causing the cutter-bar to be raised upon the rocking of said lifting member in one direction, said 110 lifting member being provided with a stepped flange extending partially about its axis of revolution, a stop device carried by said frame with which said stepped flange engages when said lifting member is turned in a direction to raise the cutter-bar, and a lever for raising said lifting member and also serving to move said stepped flange out of engagement with said stop device.

28. In a mowing machine, the combination of a frame, a cutter-bar movable relative to said frame, a lifting member revolvably mounted on said frame and movable bodily slightly up and down relative thereto, means connecting said lifting member 125

130

- and said cutter-bar for causing the cutter-bar to be raised upon the rocking of said lifting member in one direction, said lifting member being provided with a stepped flange extending partially about its axis of revolution, a stop device carried by said frame with which said stepped flange engages when said lifting member is turned in a direction to raise the cutter-bar, and a 10 foot-lever that will by a downward stroke turn said lifting member for raising the cutter-bar and at the same time raise said lifting member so as to carry said stepped flange out of engagement with said stop device. 15
29. In a mowing machine, the combination of a frame, a cutter-bar movable relative to said frame, a lever pivotally mounted on said frame, a lifting member revolvably mounted upon said lever on an axis that is eccentric relative to that upon which the lever is mounted on the frame, and means connecting said lifting member and said cutter-bar for causing the cutter-bar to be raised 20 upon the rocking of said lifting member through the turning of the lever in one direction. 25
30. In a mowing machine, the combination of a frame, a cutter-bar movable relative to said frame, a lever pivotally mounted on said frame, a lifting member revolvably mounted upon said lever on an axis that is eccentric relative to that upon which the lever is mounted on the frame, means 30 connecting said lifting member and said cutter-bar for causing the cutter-bar to be raised upon the rocking of said lifting member in one direction by the turning of the lever, and a stop device adapted to 40 operatively engage said lifting member when said lifting member is turned by said lever. 45
31. In a mowing machine, the combination of a frame, a cutter-bar movable relative to said frame, a lever pivotally mounted on said frame, a lifting member revolvably mounted upon said lever on an axis that is eccentric relative to that upon which the lever is mounted on the frame, means connecting said lifting member and said cutter-bar for causing the cutter-bar to be raised 50 upon the rocking of said lifting member in one direction, and means carried by said lever for engaging said lifting member to cause it to turn about its axis upon said lever when said lever is moved in one direction. 55
32. In a mowing machine, the combination of a frame, a cutter-bar movable relative to said frame, a lever pivotally mounted 60 on said frame, a lifting member revolvably mounted upon said lever on an axis that is eccentric relative to that upon which the lever is mounted on the frame, means connecting said lifting member and said cutter-bar for causing the cutter-bar to be raised 65 upon the rocking of said lifting member in one direction. 70
33. In a mowing machine, the combination of a frame, a cutter-bar movable relative to said frame, a lever pivotally mounted on said frame, a lifting member revolvably mounted upon said lever on an axis that is eccentric relative to that upon which the lever is mounted on the frame, means connecting said lifting member and said cutter-bar for causing the cutter-bar to 75 be raised upon the rocking of said lifting member in one direction, an arm fixedly mounted on said lever for engaging said lifting member a turning movement about its axis upon the lever for raising the cutter-bar when said lever is moved in one direction. 80
34. In a mowing machine, the combination of a frame, a cutter-bar movable relative to said frame, a lifting member revolvably mounted on said frame and bodily movable slightly up and down relative thereto 85 and provided with a stepped cam-shaped flange, means connecting said lifting member and said cutter-bar for causing the cutter-bar to be moved upon the rocking of said lifting member in one direction, and a 90 stop device carried by said frame for supporting said lifting member when said member is rocked to raise the cutter-bar and which engages the steps in the flange for holding the cutter-bar in raised position. 95
35. In a mowing machine, the combination of a frame, a cutter-bar movable relative to said frame, a lifting member revolvably mounted on said frame and bodily movable slightly up and down relative thereto 100 and provided with a stepped cam-shaped flange, means connecting said lifting member and said cutter-bar for causing the cutter-bar to be moved upon the rocking of said lifting member in one direction, a stop device carried by said frame for supporting 105 said lifting member when said member is rocked in a direction to raise the cutter-bar and which engages the steps in the flange for holding the cutter-bar in raised position, and a foot-lever for raising said lifting member relative to said frame to permit such member to rock without engaging said stop device. 110
36. In a mowing machine, the combination of a frame, a cutter-bar movable relative to said frame, a lifting member revolvably mounted on said frame and bodily movable slightly up and down relative thereto 115 and provided with a stepped cam-shaped flange, means connecting said lifting member and said cutter-bar for causing the cutter-bar to be raised 120 upon the rocking of said lifting member in one direction. 125

flange, means connecting said lifting member and said cutter-bar for causing the cutter-bar to be moved upon the rocking of said lifting member in one direction, a stop 5 device carried by said frame for supporting said lifting member when said member is rocked in a direction to raise the cutter-bar and which engages the steps in the flange for holding the cutter-bar in raised position, 10 and a foot-lever by a downward stroke of which said lifting member is given a turning movement for partially raising said cutter-bar and which also raises said stepped flange out of engagement with said stop 15 vice.

37. In a mowing machine, the combination of a frame, a cutter-bar movable relative thereto, a pivot connected with said

frame and movable vertically relative thereto, a lifting member rotatably mounted on said movable pivot, means connecting said lifting member with the cutter-bar and means for turning said lifting member on the pivot and simultaneously moving said pivot relative to the frame. 20

38. In a mowing machine, the combination of a frame, a cutter-bar movable relative thereto, a pivot journaled in said frame, a lifting member rotatably mounted on said journaled pivot, means connecting said lifting member with the cutter-bar, and means for turning said lifting member on the pivot and simultaneously moving said pivot vertically relative to the frame. 25 30
